UNITED STATES PATENT OFFICE

LAWRENCE M. PERSONS, OF CHICAGO, ILLINOIS, ASSIGNOR TO COOK ELECTRIC COMPANY,
OF CHICAGO, ILLINOIS, A CORPORATION OF ILLINOIS

PUMP

Application filed April 4, 1927. Serial No. 180,669.

My invention relates to an automatic control for fluid supply systems employed to pump liquid into a supply tank or receptacle and is particularly directed to the automatic control of a pumping apparatus which insures greater protection and safety.

In order to apprise those skilled in the art how to construct and practice my invention, I shall now describe a preferred embodiment thereof in connection with the accompanying drawings forming a part hereof.

In the drawings:

Figure 1 is a diagrammatic view of a fluid supply system embodying my invention;

Fig. 2 is an enlarged vertical sectional view of the pump;

Fig. 3 is an enlarged detail sectional view of the control, a portion of the pump head being illustrated in dotted lines;

Fig. 4 is a sectional view taken on line 4—4 of Fig. 3 looking in the direction of the arrows; and

Fig. 5 is a detail view of the control element.

It will be observed that the preferred embodiment of my invention comprises an oil burning system which is particularly employed for domestic purposes, as for instance, heating homes and other similar buildings. It will be understood nevertheless that my invention may be embodied in any type of liquid fuel feeding system, or in any type of fluid system adapted for pumping a liquid from a source of supply into a supply tank or receptacle, or otherwise.

Various types of automatic pumps have heretofore been provided embodying a control capable of automatically starting and stopping the pump according to various operating conditions. A type of pump particularly employed in liquid fuel feeding systems, which is simple and expedient to use, comprises a small receptacle into which the liquid is pumped and from which it is fed by gravity to the burner. To control the automatic operation of this type of pump, a float mechanism is incorporated in the receptacle to control the pumping unit between certain liquid levels. If the liquid falls below a predetermined low level, the

float closes the motor circuit to start operation of the pump until the liquid reaches a predetermined high level. The float then rises until this predetermined high level is reached and thereupon it opens the circuit to stop the pumping unit.

Considerable attention has been given to such an automatic control, because there is a possibility that it will function to pump the entire contents from the storage tank into the building in the event a leak occurs in the line extending from the pump to the burner, or other point of consumption. In oil burning systems particularly this is objectionable, due to the possible fire hazard arising when the basement floor is thus flooded by the liquid fuel. The Underwriters Laboratories, which approve devices of this kind, have objected to an automatic control, when it is not provided with a safety which would cut out the pump in the event a leak occurred.

I contemplate embodying my invention in any type of automatic pump. Provision is made to cut out the pump after a predetermined quantity of fuel has been pumped from the reserve supply tank into the building to the burner.

In the apparatus shown in the drawings, oil or liquid in the storage tank 5 is drawn through a suction pipe 6 constituting a suction line by means of a pump "A", and is discharged into a supply tank or other receptacle 7, from which receptacle the oil is fed to burner 10. Burner 10 may be of any desired type, although I have shown a motor 11 for driving a blower 12, which blower feeds the liquid fuel in an atomized condition to a fire pot 13.

Pump "A" comprises an electric motor 14 provided with a worm 15 meshing with a worm gear 16 mounted on a shaft 17, having an eccentric connection 18 which is adapted to drive a piston 19 suitably embodied in a cylinder 20 connected to the base of motor 14. Receptacle 7 may also be attached to this motor base and is arranged to enclose the pump cylinder 20. During the pulsations of piston 19, the liquid fuel is drawn through suction pipe 6 into port 21 through a strainer

22 and into pump cylinder 20 through an inlet valve not shown herein, but more fully described in United States Letters Patent, No. 1,746,441, granted to me on February 11, 1930. In this patent I have also described the manner of discharging the fuel from the cylinder 20 into receptacle 7. During the normal operation of pump "A", the level of the liquid will fluctuate between the high level "A-B" and the low level "C-D". When the liquid reaches low level C-D, the motor circuit is closed by float 25 dropping to close an electric switch 26 suitably connected in the motor circuit by the conductors 10 27. The pumping unit will continue pumping until the level reaches the high level A-B. Thereupon the float rises to open switch 26.

In the event that the delivery pipe 28 between pump A and burner 10 leaks or is broken, the abnormal discharge of liquid from receptacle 7 lowers the float and allows continuous operation of the pumping unit to pump the liquid from the reserve supply tank 5 into the building. To prevent the building from being flooded, my invention provides means for automatically stopping the pump after a predetermined quantity of fuel is drawn from the reserve supply tank 30 by pump A.

This means comprises an automatic cut out unit 30, which may be suitably attached to the housing of motor 14, as shown in Figs. 3 and 4. The unit includes a housing 31 enclosing a speed reducing connection "B" between the motor drive and a controlling element "C" connected in the motor circuit. Shaft 17 is mounted in bearings 32 and 33, as indicated in Fig. 3, and is connected by a suitable coupling 34 to a shaft 35 having a worm 36 secured thereto. Suitable bearings 37 and 38 are mounted on housing 31 to support a transversely arranged shaft 39, on which a worm gear 40 is fastened. Worm gear 40 is adapted to mesh with worm 36 to drive the transversely arranged shaft 39. A second worm 41 is formed on shaft 39 to mesh with a second worm gear 42. Worm gear 42 is suitably secured to a shaft 43, journaled in suitable bearings 44 and 45 supported by housing 31. Another worm 47 is carried by shaft 43 to mesh with and drive a worm gear 48 secured to shaft 49 mounted in a bearing 50 supported in one side of housing 31. The inner end of shaft 49 is tapered at 51 to provide a frictional engagement with controlling element C. This element is preferably formed of insulating material having an annular contact 55 carried about its periphery. Contact 55 does not extend about the entire periphery of controlling element C, but is broken as indicated at 56 in Fig. 5. The gear train described reduces the speed of rotation of controlling element C, so that the latter will rotate once during the pumping

of predetermined quantity of fluid by the pump.

Controlling element C is connected in circuit with the motor 14 by means of a contact 57 and a coil spring 58. Motor conductor 59 suitably connects to contact holder 60 at 61, and the contact 57 may be carried by the holder 60. The other motor conductor 62 is fastened to a metallic annular member 63 carried by an insulating plate 64, which insulating plate may be suitably secured to the housing, or otherwise. It is obvious that the circuit is completed through coil spring 58, which bears against plate 63 and the contact 55 carried by controlling element C. After a predetermined quantity of liquid has been pumped, the controlling element C will have rotated to the point where contact member 55 is broken, so that the contact 57 drops onto the surface 56 of the controlling element. This opens the motor circuit and stops the pump.

It is apparent that the pumping unit is capable of supplying a predetermined quantity of liquid before it automatically stops. This quantity may vary according to the requirements of the installation, but I might mention that in oil burning systems, it is desirable to allow the pumping unit to pump sixty (60) gallons of liquid fuel from the reserve supply tank to the burner before allowing the controlling element C to open the circuit. It has been ascertained that sixty gallons is insufficient to cause a fire hazard in the event of a leak in the delivery pipe 28.

Another advantage of my invention is that manual resetting of the pump is required after it automatically stops in the manner just described. This requires the occupant of the building to inspect the pump periodically, although it is automatic in operation. Obviously, he will be compelled to observe the operating conditions of the burner and the amount of oil remaining in the bulk supply tank 5. It prevents the user of the system entirely to overlook the heating unit and allow the supply of liquid fuel in reserve supply tank 5 to be exhausted. To allow the supply in tank 5 to be exhausted, requires the system to be shut down for a number of hours or until such time as the supply may be replenished, and, in cold weather, this is dangerous because during such times the piping in the building is apt to freeze and burst.

The manual resetting mechanism comprises a plunger 65 having a suitable knob 66 mounted at the end thereof. The inner end of plunger 65 threads into controlling element C, or is otherwise suitably fastened, to permit manual rotation in order to bring a starting point of contact member 55 into engagement with the fixed contact 57. The frictional engagement between shaft 49 and controlling element C may be temporarily broken by pulling the knob 66 outwardly

against the action of spring 58. During normal operation, however, spring 58 applies sufficient force to hold controlling element C in driving relation with the tapered end 51 of shaft 49.

Any suitable speed reducing gearing may constitute the connection B between the rotor drive and controlling element C. I do not intend to be limited to any particular speed reduction or to the employment of speed reducing gearing as a connection between the motor drive and the controlling element. My invention primarily resides in the provision of a controlling element having a plurality of positions which, during its movement, will maintain the pumping unit in operation, while in one of its positions, and which will automatically stop the pumping unit, when another position is reached.

Various modifications and alterations of the various parts and mechanisms described may be had without departing from the scope of the invention.

I claim:

1. The combination with liquid feeding apparatus including a pump, a motor and a circuit for said motor, of a control for stopping said pump, after a predetermined operation, having means for opening said motor circuit, said means including a spring pressed rotating member, a drive between said member and said motor, a contact on said member for opening said motor circuit after a predetermined rotation of said member, and means for disengaging said member from said drive to reset said contact to circuit closing position.

2. The combination with liquid feeding apparatus including a pump, a motor and a circuit for said motor, of a control for stopping said pump, after a predetermined operation, having means for opening said motor circuit, said means including a rotating member, a drive between said member and said motor, a contact on said member for opening said motor circuit after a predetermined rotation of said member, and means for disengaging said member from said drive to reset said contact to circuit closing position.

3. The combination with liquid feeding apparatus including a pump, a motor and a circuit for said motor, of a control for said pump having means for opening said motor circuit after a predetermined operation of said pump including a relatively fixed contact and a rotating contact engaging said fixed contact during a portion of its rotation and disengaging thereafter to open said motor circuit, and means for resetting said rotating contact to close said motor circuit.

4. The combination with liquid feeding apparatus including a pump, a motor and a circuit for said motor, of a control for said pump having means for opening said motor circuit after a predetermined operation of

said pump including a rotating clutch member in driving relation with said motor, a contact rotated by said member, a second contact engaging said rotating contact during a portion of its rotation, and means for temporarily disengaging said rotating clutch member from driving relation with said motor.

5. The combination with liquid feeding apparatus including a pump, a motor and a circuit for said motor, of a control for said pump having means for opening said motor circuit after a predetermined operation of said pump including a rotating clutch member, a drive for said clutch member, spring means for urging said clutch member in operative relation with said drive, means for overcoming said spring means to permit disengagement of said clutch member, a contact carried by said clutch member, and a relatively fixed contact adapted to be engaged by said first contact during a predetermined rotation of said clutch member.

In witness whereof, I have hereunto subscribed my name.

LAWRENCE M. PERSONS.
